his Attorney.

UNITED STATES PATENT OFFICE.

WARDER D. HUNT, OF CINCINNATI, OHIO.

BED-BOTTOM.

SPECIFICATION forming part of Letters Patent No. 733,650, dated July 14, 1903.

Application filed November 4, 1901. Serial No. 81,069. (No model.)

To all whom it may concern:

Be it known that I, WARDER D. HUNT, a citizen of the United States of America, and a resident of Cincinnati, in the county of Hamilton and State of Ohio, have invented certain new and useful Improvements in Bed-Bottoms, of which the following is a specification.

This invention relates to certain improvements in spring bed-bottoms, and more especially in that class of bed-bottoms or spring-mattresses which are formed from a spring structure covered over with a sheet of woven-wire fabric; and the object of the invention is to provide a bed-bottom of this general character of a strong, light, and durable nature and of a simple and inexpensive construction having improved means for holding the woven-wire covering-sheet in position upon the top of the structure.

The invention consists in certain novel features of the construction, combination, and arrangement of the several parts of the improved spring bed-bottom or mattress whereby certain important advantages are attained and the device is made simpler, cheaper, and otherwise better adapted and more convenient for use, all as will be hereinafter fully set forth.

The novel features of the invention will be carefully defined in the claims.

In the accompanying drawings, which serve to illustrate my invention, Figure 1 is a plan view showing a spring bed-bottom or mattress embodying my improvements. Fig. 2 is a view showing a metal strip such as is employed for forming the end rail to which the woven-wire covering-sheet is attached at its end. Fig. 3 is a sectional view taken transversely through said strip and showing the first bend produced therein in the course of attaching the woven-wire covering-sheet thereto. Fig. 4 is a view similar to Fig. 3, but showing the strip provided with its second bend. Fig. 5 is a view similar to Figs. 3 and 4, but showing the third bend produced in the metal strip. Fig. 6 is a view similar to Figs. 3, 4, and 5, but showing the metal strip provided with its fourth bend. Figs. 7 and 8 are views similar to Figs. 3 to 6, but drawn to a larger scale and showing the metal

strip provided with its fifth and sixth bends. Fig. 9 is a side view, and Fig. 10 a plan view, showing the clip for connecting the side and end rails of the spring structure.

As shown in the views, the spring structure comprises a top frame of rectangular form produced from side rails 1 1 and end rails 2 2. A sheet 3, of woven-wire fabric, is extended across this rectangular top frame, being attached at its ends to the end rails 2 2, as will be hereinafter explained. For supporting the top frame helical springs 4 4 are employed, disposed uniformly beneath the woven-wire covering 3 and having their upper end coils held by intersecting cross-wires 5 5, which are extended in two series across the top frame, each series being at right angles to the other. The ends of these cross-wires are connected, by means of loops or the like, with the side and end rails 1 and 2 and serve to brace and strengthen the structure in a well-known way.

At the corners of the rectangular top frame the side and end rails 1 and 2 thereof are connected together by means of clips or fastening means 6, herein shown as formed from sheet metal bent to shape and having tubular shanks 7, in which the ends of the side rails 1 are engaged, and also provided with lateral extensions 8 at their ends, in which the extremities of the end rails 2 of the top frame are engaged. The extensions 8 of the clips are extended at right angles to the inner sides of the shanks 7 thereof and are provided with upper and lower projecting parts 8 8 or wings 9 9, adapted to be bent or clenched toward each other along the inner sides of the end rails 2 of the top frame in order to more securely connect said end rails to the side rails, as will be more fully hereinafter explained.

Each end rail 2 is produced from an elongated strip or piece of sheet metal, such as is shown in detail in Fig. 2, this strip having a central crease or bend produced in it, as shown at *a* in Fig. 3 and indicated in dotted lines in Fig. 2, this central bend giving to the strip a V shape in cross-section, as clearly shown in Fig. 3. The end of the woven-wire covering-sheet 3 is then inserted between the 100

two plies 10 10 produced by the central bend *a* in said strip, after which the two plies 10 10 are pressed flat upon each other, as indicated in Fig. 4, the end of the woven-wire sheet 3 being thereby flattened out and held between said plies 10. A second central bend or crease *b* is then produced in the folded strip 2, as indicated in Fig. 5, and the two plies 11 11 produced in the strip by said bend or crease are also pressed flat upon each other, as shown in Fig. 6, whereby it will be seen that the end of the woven-wire sheet 3 is securely held between the plies of the folded strip. A third and final central bend or crease *c* is then produced in the folded strip, as shown in Fig. 7, and the two plies 12 12 thus formed are also pressed flat upon each other, as shown in Fig. 8, whereby the folded metal strip is given a rounded shape in cross-section and is formed into substantially a straight metal rod or bar without sharp or rough projections and of considerable thickness and rigidity, such as is suitable for use as the end rail of the spring structure. The ends of the end rail or bar 2 thus produced are inserted in the sockets formed by the hollow extensions 8 of the clips 6, and when in place the projecting parts or wings 9 are pressed or clenched toward each other, as shown in Fig. 8, their inner adjacent edges engaging upon the upper and lower faces of the woven-wire covering-sheet 3 in such a way as to bind against the same, and thereby to securely hold the end rails 2 connected to the side rails 1 of the structure. The tubular shanks 7 of the clips 6 are slit along their inner sides, so that when slipped over the ends of the side rails 1 they may be pressed tightly upon said rails for holding them securely thereon.

The improved spring bed-bottom or mattress constructed as above described is of an extremely light, strong, and durable nature and combines all of the best advantages of an ordinary spring bed-bottom with those of the woven-wire covering-sheet, so that the device is of an extremely useful nature and may be readily cleaned. The ends of the woven-wire covering-sheet are also securely attached to the top frame of the structure and cannot be pulled loose therefrom, and since said ends are housed within the folds of the sheet-metal strips, of which the end rails 2 are formed, they present no rough or sharp edges or points to tear the bedding. The employment of the folded metal bars or rods as end rails for the spring structure also permits an economy in the manufacture, and since the extensions 8 are projected at right angles to the shanks 7 of the clips it will be seen that provision is made for extending the woven-wire covering-sheet entirely across the top frame of the mattress, as indicated in Fig. 1. The edges of the woven-wire sheet 3 are also by preference attached at intervals to the side rails 1 of the top frame, and this

attachment may be by means of loops 14, as indicated in Fig. 1, or otherwise. It will also be obvious from the above description that the improved bed-bottom or spring-mattress is capable of considerable modification without material departure from the principles and spirit of the invention, and for this reason I do not wish to be understood as limiting myself to the precise form and arrangement of the several parts of the device as herein set forth in carrying out my invention in practice.

Having thus described my invention, I claim—

1. In a spring-mattress or the like, the combination of a spring structure comprising a top frame formed of end rails and side rails and having cross-wires extended at right angles across it and intersecting with each other and spiral springs having end coils engaged with said cross-wires and a covering-sheet of woven-wire fabric extended across said top frame and over said cross-wires and having the ends of its strands secured to the opposite end rails of said top frame, substantially as set forth.

2. In a spring-mattress or the like, the combination of a spring structure comprising a top frame formed of end rails and side rails and having cross-wires extended at right angles across it and intersecting with each other and spiral springs having end coils engaged with said cross-wires and a covering-sheet of woven-wire fabric extended across said top frame, and over said cross-wires the end rails of said frame being formed of metal strips folded upon themselves and connected at their ends with the side rails and the ends of the strands of the woven-wire fabric being held between the plies of said folded strips, substantially as set forth.

3. In a spring-mattress or the like, the combination of a spring structure comprising a top frame formed of end rails and side rails, clips connecting the side rails and end rails at the angles of said frame and having tubular shanks in which the ends of the side rails are engaged and sockets in which the ends of the end rails are engaged, cross-wires extended at right angles across the top frame and intersecting with each other and spiral springs having end coils engaged with said cross-wires and a covering-sheet of woven-wire fabric extended across said top frame, the end rails of said frame being formed of metal strips folded upon themselves and between the plies of which the ends of the strands of the woven-wire covering-sheet are held, substantially as set forth.

4. In a spring-mattress or the like, the combination of a spring structure comprising a top frame formed of end rails and side rails and having cross-wires extended in two series at right angles to each other across said top frame, the wires of one series being secured to the side rails and those of the other series

being secured to the end rails and spiral springs having end coils engaged with the cross-wires at their intersections, the end rails of the frame being formed of metal strips

5 folded upon themselves and a covering-sheet of woven wire extended across the top frame and oversaid cross-wires and having the ends of its strands held between the plies of the

folded strips of which the end rails of said frame are formed, substantially as set forth. 10

Signed at Cincinnati, Ohio, this 31st day of October, 1901.

WARDER D. HUNT.
